DESIGN FOR A BOTTLE

Fred R. Hoch, Bristol, Mass., assignor to T. J. Holmes Co. Inc., Chartley, Mass., a corporation of Massachusetts

Application March 5, 1941, Serial No. 99,365

Term of patent 7 years

To all whom it may concern:

Be it known that I, Fred R. Hoch, a national of the German Reich, residing at Norton, in the county of Bristol and Commonwealth of Massachusetts, have invented a new, original, and ornamental Design for a Bottle, of which the following is a specification, reference being had to the accompanying drawing, forming a part thereof, in which—

I claim:

The ornamental design for a bottle substantially as shown.

FRED R. HOCH.
